UNITED STATES PATENT OFFICE.

GILBERT SMITH AND JOHN J. WELLS, OF SAN FRANCISCO, CALIFORNIA.

COIN TESTER AND INDICATOR.

SPECIFICATION forming part of Letters Patent No. 259,338, dated June 13, 1882.

Application filed November 14, 1881. (No model.)

To all whom it may concern:

Be it known that we, GILBERT SMITH and JOHN J. WELLS, citizens of the United States, and residing at San Francisco, in the county 5 of San Francisco and State of California, have invented a new and useful Coin Tester and Indicator, of which the following is a specification.

The object of our invention is to provide a 10 means whereby spurious coins and coins of short weight may be easily and quickly detected.

We accomplish this object by the device illustrated in the accompanying drawings, in 15 which—

Figure 1 is a front elevation of the dial with cap for covering the mechanism in position. Fig. 2 is also a front elevation of the dial and stand with cap removed. Fig. 3 is a vertical 20 section in elevation.

Similar letters refer to similar parts throughout the several views.

Our indicating-dial A is mounted upon a stand, as shown, and provided with a scale for 25 testing gold coins of the denomination of two dollars and a half, (\$2½,) five dollars, (\$5,) ten dollars, (\$10,) and twenty dollars, (\$20,) and the word "gold" is marked beneath these figures, which figures and scale occupy about one-quarter of the face of the dial. Beneath this 30 gold-scale, above described, we place the scale for silver coins, which consists of the numerals five, (5,) ten, (10,) twenty, (20,) twenty-five, (25,) fifty, (50,) and one hundred, (100,) the latter 35 representing one dollar, or one hundred cents, and the former figures from five cents to fifty cents. This scale is designated by the word "silver."

The hands or pointers B B' operate on a pin, 40 C, upon the face of the dial, the outer end of which is split to receive a spring, D, which latter connects with the arm of the coin-holder E. To the lower end of the arm of the coin-holder is connected a bent pin, n, which operates in a 45 slot made in the pointer or hand B', so as to give play to the coin-holder and take away that rigidity of the parts which a close connection would have or if the arm were permanently fixed to the hand. The upper end of the coin-holder is a flattened piece of metal, and is bent 50 over upon itself to form a slot, F, to receive the

edge of a coin and retain it in position while being tested.

In practice we make the spring of such tension, and adjust the indicators or hands with 55 reference thereto, that when a genuine piece of coin is put into the receiver or coin-holder the denomination will be registered or indicated by one of the pointers or hands upon the dial, either in gold or silver, as the case may 60 be. For instance, if the coin be a five-cent piece the silver-indicating hand will point to and be in the exact line with the figure 5 on the dial, and so on from the smallest denomination to the largest, on both the gold and 65 silver scales. Should the coin, however, be counterfeit, or the weight thereof be short by reason of its having been tampered with, the hands will fall short of the figures or marks of the scale which the coin represents, and thus 70 show to a certainty that the coin should be rejected.

It will thus be clearly seen that in the use of our device persons who are unskilled in the weight and value of coins will be put on guard 75 against that deception which is now so largely practiced in money exchanges.

Having thus described our invention, what we claim, and desire to secure by Letters Patent, is—

1. The dial A, provided with gold and silver numerals and scales, in combination with the hands, pointers, or indicators operated by a spring, so that when a weight or coin is placed upon the coin receiver or holder the hand will 85 point to that numeral upon the dial that represents the value of the coin placed in the receiver or holder, substantially in the manner as herein set forth and specified.

2. In a coin tester and indicator, the combination of the dial A with the hands or pointers B, spring D, and coin-holder E, constructed and operating substantially in the manner as herein set forth and specified.

In testimony that we claim the foregoing we 95 have hereunto set our hands this 27th day of October, 1881.

GILBERT SMITH.
JOHN J. WELLS.
